UNITED STATES PATENT OFFICE

CHARLES W. WARNER, OF MIDDLETOWN, CONNECTICUT, AND THOMAS M. KEEFE, OF BOSTON, MASSACHUSETTS

DESIGN FOR A BRACKET FOR TOWEL BARS OR SIMILAR ARTICLES

Application filed July 30, 1929. Serial No. 32,248. Term of patent 7 years.

To all whom it may concern:

Be it known that we, CHARLES W. WARNER and THOMAS M. KEEFE, citizens of the United States, residing, respectively, in Middletown, Middlesex County, Connecticut, and Boston, Suffolk County, Massachusetts, have invented a new, original, and ornamental Design for a Bracket for Towel Bars or Similar Articles, of which the following is a specification, reference being had to the accompanying drawing, forming a part thereof, and in which:—

Figure 1 is a side elevation of the article, showing our new design;

Fig. 2 a top plan view;

Fig. 3 a side elevation as viewed from the top of Fig. 2, and

Fig. 4 is an end elevation as viewed from the front.

We claim:

The ornamental design for a bracket for towel bars or similar articles, as shown.

CHARLES W. WARNER.
THOMAS M. KEEFE.
